DUAL ROTARY PUMP FOR POWER TRANSMISSIONS

Duncan B. Gardiner, Detroit, Mich., assignor to
 Vickers Incorporated, Detroit, Mich., a corporation of Michigan

Application December 14, 1948, Serial No. 65,157

11 Claims. (Cl. 103—4)

1

This invention relates to power transmissions and is particularly applicable to those of the type comprising two or more fluid pressure energy translating devices, one of which may function as a pump and another as a fluid motor.

The invention is generally concerned with multiple pumping units and is more particularly concerned with a dual pumping unit of the rotary vane type. Units of this type are adaptable for use in hydraulic power transmissions having a plurality of fluid motors which must be separately driven. Although each pumping unit is separately connected to a fluid motor for separately operating the same, the pumps may be driven from a common prime mover and supplied with fluid from a single fluid supply source. Multiple pumping units of this type are also utilized with control valves adapted to cooperate therewith in circuits wherein a large volume of fluid is required against a fairly low pressure and at other times a smaller volume of fluid is required against a high pressure. The latter type of circuit is common in machine tool drives where a large volume of fluid is required for rapidly advancing a machine part to its working position and where a small volume of fluid is required for slowly feeding the part on its working stroke. In addition, there are many different hydraulic circuits which may utilize a plurality of pumps in various other ways.

Multiple pumping units have been provided for circuits of the type mentioned which have been proven efficient and which are more economical than the use of separate pumps because of combining in one compact unitary structure the multiple pumping units required for the purposes of the circuit. However, because of the great variety of circuits in which multiple pumping units may be incorporated and the different volume and pressure requirements of each circuit it has been necessary to provide a variety of multiple pumping units to meet the various circuit volume and pressure requirements. One popular type of multiple pumping unit of the dual rotary vane type comprises two pumping units identical as to construction, each of which comprises a cam ring having an inner elliptical surface within which a rotor carrying reciprocal vanes to form working chambers is mounted. Each rotor has to be supported by oppositely positioned bushing units containing porting adapted to cooperate with fluid passages in the casing to provide an inlet and outlet for fluid to and from the working chamber of each pumping unit. In addition, each pumping unit has to be

5 retained in their respective pumping recesses by separate means, usually by head plates which have to be independently mounted and adapted to fit snugly in their recesses to insure equal distribution of clamping pressure over their respective units. In some cases, in addition to separate head plates, bearing plates are provided which are mounted independently of the head plate so as to avoid adjustment which would interfere with the clamping pressure and cause binding.

10 The present invention obviates the use of separate bushings for each pumping unit by providing a valve plate common to both pumping units and also avoids the use of separate head plates by utilizing a novel pressure head and pressure plate construction which are connected to the discharge side of the pumping units and automatically maintain both rotors in fluid sealing engagement with the valve plate. The present invention avoids the disadvantages of other constructions where it is necessary to mechanically adjust the clamping pressure to provide fluid sealing engagement of the rotary pumping units.

15 20 25 30 It is therefore an object of this invention to provide an improved multiple pumping unit of the rotary vane type.

It is also an object of this invention to provide a dual rotary vane pumping unit which is readily adaptable for interchangeability to meet a variety of circuit pressure and volume requirements.

35 40 It is also an object of this invention to provide a dual rotary vane pumping unit which eliminates the use of separate supporting bushings for each pumping unit.

It is a further object of this invention to provide a dual rotary vane pumping unit which also eliminates the use of any mechanical adjustable 45 clamping means for maintaining the rotary pumping units in fluid sealing engagement against their respective cooperating stationary bearing surfaces.

It is an additional object of this invention to 50 eliminate separate bushing elements for each rotary vane pumping unit by providing a valve plate common to both rotors and to provide a fluid sealing engagement of the rotors with the valve plate by pressure responsive means.

55 It is also an object of this invention to provide

a dual rotary vane pumping unit which is of an improved, simplified, compact, and reliable construction, which may be produced at low cost and which because of interchangeable features will meet a variety of circuit requirements.

Further objects and advantages of the present invention will be apparent from the following description, reference being had to the accompanying drawings wherein a preferred form of the present invention is clearly shown.

In the drawings:

Figure 1 is a longitudinal sectional view of a preferred form of the present invention on line 1—1 of Figure 2.

Figure 2 is a top view of the present invention.

Figure 3 is a sectional view on line 3—3 of Figure 1.

Figure 4 is a sectional view on line 4—4 of Figure 1.

Figure 5 is a sectional view on line 5—5 of Figure 1.

Figure 6 is a sectional view on line 6—6 of Figure 1.

Figure 7 is a partial sectional view on line 7—7 of Figure 5.

Figure 8 is a sectional view on line 8—8 of Figure 1.

Figure 9 is a partial sectional view on line 9—9 of Figure 3.

Figure 10 is a partial sectional view on line 10—10 of Figure 3.

Referring to Figure 1, there is shown a dual rotary pumping unit 10 having a casing which preferably is in three sections consisting of a right end section 12, a left end section 14, and a center section 16, all of which are connected together by suitable screws 18, two of which are shown in Figure 2. The right end section 12 is provided with a common inlet supply flange 20 and the left end section with independent outlet delivery flanges 22 and 24 for two pumping units of identical construction but of different sizes, one of which is mounted in the center section 16 and indicated by the numeral 26, and the other of which is mounted in the left end section 14 and indicated by the numeral 28.

The pumping units 26 and 28, shown more clearly in Figures 4 and 8, respectively, comprise rotors 30 and 32, each of which carry a plurality of reciprocating vanes 34 held in bearing contact with the inner contours of their respective cam rings 16 and 38, the former of which comprises the center section of the unitary casing. The rotors 30 and 32 are mounted on a common drive shaft 40 which is splined at 42 and 44 to provide a driving connection for each of the pumping units. The casing section 12 carries bearings 46 and 48 in which the shaft 40 is rotatably mounted and a suitable sealing ring indicated by the numeral 50.

The inner contours of the cam rings 16 and 38, which are respectively indicated by the numerals 52 and 54, are generally elliptical in shape to provide balanced working chambers 56 and 58 for the larger pumping unit and balanced working chambers 60 and 62 for the smaller unit.

The right end casing section is provided with an inlet passage indicated by the numeral 64 which registers with the inlet connection 20 (Figure 1) and which is branched, said branches being indicated by the numerals 65 and 67 and each being respectively provided with an arcuate shaped port at its termination indicated by the numerals 66 and 68 and shown in Figure 3.

The ports 66 and 68 register, respectively, with

a portion of the working chambers 56 and 58 of the larger pumping unit, and also register, respectively, with a plurality of port holes 70 and a duplicate plurality of port holes 72 in the cam ring 16, the latter of which are respectively located immediately adjacent to the working chambers 56 and 58. The series of port holes 70 and 72 which extend completely through the ring 16 cooperate, respectively, with a pair of arcuate shaped inlet ports 78 and 80 in a fluid distributing valve plate or cheek plate 82 (Figures 1 and 5) which is mounted in the left end casing section 14 so as to provide a supply of fluid to the inlet side of the smaller pumping unit.

As shown in Figures 1 and 3, the plurality of port holes 70 and 72 register respectively on the right side of the cam ring 16 with inlet ports 66 and 68 of the casing section 12 and on the opposite side register, respectively, with the arcuate inlet ports 78 and 80 of the valve plate 82.

Referring to Figures 1 and 5, a curved passage 84 of the valve plate 82 connects the arcuate inlet port 78 with an arcuate inlet port 86 on the opposite side of the valve plate 82 while a duplicate curved passage 88 connects the arcuate inlet port 80 with an arcuate inlet port 90 on the opposite face of the valve plate 82. The arcuate inlet ports 86 and 90 register, respectively, with a portion of the working chambers 60 and 62 of the smaller pumping unit shown in Figure 8. In addition to the arcuate inlet ports located on opposite sides of the valve plate 82, the latter is also provided with arcuate delivery ports 92 and 94 for the large pumping unit 26 (Figure 5) which extend completely through the valve plate. The arcuate delivery ports 92 and 94 register on the right side of the valve plate with the remaining portions of the working chambers 58 and 56 of the larger pumping unit as shown in Figure 4.

Although the ports 92 and 94 should not appear in Figure 4, which is a view on line 4—4 of Figure 1, the ports have been shown in dotted lines in Figure 4 for the purpose of illustrating the registry of said ports with the remaining portion of the working chambers 58 and 56. The delivery ports 92 and 94 register on the opposite side of the valve plate 82 with an outlet chamber 96 which is formed in the left end casing section 14 (Figure 7). As the ports are duplicates and register with the outlet chamber 96 in the same manner, it has been deemed sufficient to show only one of said ports in Figure 7. The outlet chamber 96 is connected directly to an outlet passage 98, the latter of which registers with the outlet opening in the outlet flange connection 24.

The outlet chamber 96 is formed in the left end casing section 14 in the following manner. The valve plate 82 is mounted in the casing section 14 which is hollow. Mounted on the valve plate 82 is the cam ring 38 and a closure member 100. The cam ring 38 and closure member 100 are fastened to the valve plate 82 by means of screws indicated by the numeral 102. Thus, the outlet chamber 96 constitutes the space of the end section 14 between the outer peripheries of the closure member 100, the cam ring 38, and the exposed portion of the valve plate 82, and the walls of the hollow portion of the section 14.

The valve plate 82 and also the cam plate 38 and the head plate 100 which are connected thereto, are prevented from rotary movement by means of pins 104, one of which is shown in Figure 9 which extends through the large cam ring 16 and projects on either side thereof into

the right end casing section 12 and the valve plate 82.

The outer ends of the vanes of the larger pumping unit 26 are maintained against the inner periphery 52 of the cam ring 16 by means of pressure. This is accomplished by connecting the delivery ports 92 and 94 of the larger pumping unit 26 which are located in the valve plate 82 to a groove 106 of the rotor 30 by means of passages 108 and 109 and delivery passages 110 and 111 in the valve plate 82 (Figures 4, 5 and 7). As shown in Figure 4, the inner ends of slots 112 within which the vanes 34 reciprocate are rounded, as indicated by the numeral 113, and are connected to the groove 106. Thus, pressure fluid delivered by the pumping unit 26 to the delivery port 92 is delivered by the passages 108 and 109 to the groove 106 while pressure fluid delivered through the delivery port 94 is directed to the groove 106 by means of passages 110 and 111.

Fluid delivery from the smaller pumping unit 28 is delivered to a separate outlet passage 114 which registers with the opening in the outlet flange 22 as follows. Referring to Figures 1 and 6, mounted within the closure member 100 is a pressure loaded cheek plate 115 for a smaller pumping unit 28 which contains arcuate delivery ports 116 and 118 extending completely through the plate. These ports are connected to the outlet side of the pumping unit 28 on one side of the plate and on the opposite side of the plate are connected to a separate outlet chamber 120 of the smaller pumping unit which is formed within the closure member 100.

The outlet ports 116 and 118 of the pressure loaded cheek plate 115 are shown in Figure 6 while Figure 8 discloses the manner in which the ports 116 and 118 register, respectively, with a portion of the working chambers 62 and 60 of the smaller pumping unit 28. A telescoping fluid connection member 122, one end of which is mounted in a bore 124 of the casing section 14 and the other end of which is mounted in a bore 126 of the closure member 100 connects the outlet chamber 120 directly to the outlet passage 114. In addition the member 122 acts as a blocking valve in preventing fluid delivery from the outlet side of the large pumping unit in outlet chamber 96 from entering the outlet passage 114 of the smaller pumping unit. It can be clearly seen that bore 124 is actually a portion of the outlet passage 114 and is connected to the hollow portion of casing section 14. By locating the telescoping fluid connection member 122, as illustrated, fluid delivered from the smaller pumping unit through the delivery ports 116 and 118 of the cheek plate 115 into the outlet chamber 120 is directed through the member 122 to the outlet passage 114, and is prevented from entering the outlet chamber 96 of the large pumping unit. Conversely, fluid delivered from the larger pumping unit through the valve plate delivery ports 92 and 94 into the outlet chamber 96 of the larger pumping unit is prevented from flowing into the outlet passage 114 of the smaller pumping unit.

Means for maintaining the outer edges of the vanes of the smaller pumping unit 28 against the inner contour 54 of the smaller cam ring 38 is provided by a plurality of holes 128 in the cheek plate 115 (Figure 6) which extend therethrough and permit pressure fluid from the outlet chamber 120 to enter a groove 130 of the small rotor (Figure 8). The slots for the vanes of

the smaller rotor are identical in construction with that of the larger rotor except as to size and are rounded at their inner ends as indicated at 132. The groove 130 is in communication with the rounded portion of the slots and thus pressure fluid from the outlet chamber 120 enters the groove 130 through the plurality of holes 128 and maintains the outer edges of the vane in engagement with the inner contour 54 of the cam ring 38.

One of the most important features of the dual pumping unit is the provision for automatically maintaining both rotors in fluid sealing engagement with the single valve plate by pressure fluid means. As shown in Figure 1, it should be noted that the valve plate 82 is slightly shiftable axially in a mounting recess of the casing section 14 indicated by the numeral 134. However, the valve plate 82 is maintained by pressure fluid in the rightward position shown in engagement against a portion of the surface area of the cam ring 16 and in fluid sealing engagement with the total surface area of one side of the large rotor 30. Pressure fluid in the outlet chamber 96 of the large pumping unit acts against the left surface area of the closure member 100 and a portion of the outer surface of the valve plate 82 to maintain the valve plate 82 in fluid sealing engagement with the rotor 30. The total effective surface area included amounts to the total surface area of the valve plate 82 minus the area of the member 122. If, for any reason, the pressure in the outlet chamber is extremely low, the valve plate 82 is still maintained in fluid sealing engagement with the rotor 30 by means of light springs 135 mounted in the outlet chamber 96 on guide pins 136 the latter of which are mounted in the valve plate 82 and extend therefrom into the outlet chamber 96.

Separate means for maintaining the smaller rotor 32 in fluid sealing engagement with the opposite surface of the valve plate 82 is provided by the cheek plate 115, the surface area of one side of which is exposed to pressure in the outlet chamber 120 of the smaller pumping unit. In case of extremely low pressure in the outlet chamber 120, a light spring 138 mounted in the outlet chamber 120 will hold the cheek plate 115 in fluid sealing engagement with the small rotor 32 and against a portion of the upper surface of the small cam ring 38. The pressure loaded cheek plate also maintains the rotor 32 in fluid sealing engagement with the valve plate 82.

The cheek plate 115 is prevented from rotary movement by pins 140 shown in Figure 10 which are mounted in the cam ring 38 and extend therefrom into the closure member 100 and the valve plate 82. Suitable seals 142, 144, and 146 are provided, respectively, for the inlet flange 20 and the outlet flanges 144 and 146. Suitable sealing rings 148 and 150 are also provided for sealing engagement between the center section 16 and the end section casings 14 and 12.

In operation, with a suitable supply source of fluid connected to the inlet flange 20, fluid will enter the inlet flange 20 and the inlet passage 64, the latter of which is branched and terminates in arcuate inlet ports indicated by the numerals 66 and 68. As the rotor 30 is rotated by the shaft 40, fluid will enter that portion of the working chambers 56 and 58 in registry with the arcuate inlet ports 66 and 68 of the end casing 12. Pressure fluid will be drawn into

a portion of the working chamber 60 of the smaller pumping unit by means of the plurality of holes 70 in the center section 16, valve plate inlet port 78, passage 84, and port 86. Pressure fluid will also be drawn into a portion of the working chamber 62 of the smaller pumping unit by means of the plurality of port holes 72, valve plate inlet port 80, passage 88, and port 90. Pressure fluid will be discharged from the remaining portion of the working chambers 56 and 58 of the larger pumping unit through the delivery ports 94 and 92 which register with a portion of the working chambers 56 and 58 of the larger pumping unit. Fluid delivery from the delivery ports 92 and 94 of the valve plate 82 enters the outlet chamber 96 of the larger pumping units and from the outlet chamber 96 is delivered to the outlet passage 98 and through the outlet connection flange 24. Fluid delivery from the smaller pumping unit is delivered from the remaining portions of working chambers 60 and 62 through the pressure delivery ports 118 and 116 of the cheek plate 115 from whence fluid is delivered to the outlet connection 22 via the smaller outlet chamber 120, member 122, and outlet passage 114. The member 122 prevents fluid delivery from the larger pumping unit entering the outlet passage 114 of the smaller pumping unit and conversely prevents fluid delivery from the smaller pumping unit entering the outlet chamber 96 and outlet passage 98 of the larger pumping unit.

As can be clearly seen, the pumping action of both pumping units is similar to the vane pump described in the patent to Harry F. Vickers, No. 1,989,900. The shape and dimensions of the working chambers of the pumping units cooperate with the shape and arrangement of the inlet and outlet ports to provide vane pumps of the balanced type.

It is important to note that the use of supporting bushings have been completely eliminated. The construction of the valve plate is such that it cooperates with inlet passages in the right end casing section 12 and the center section 16 to distribute fluid to the inlet side of the smaller pumping unit. In addition, the valve plate contains delivery ports which connect the outlet side of the large pump to the outlet chamber and outlet passages for the large pump in the left end casing sections. The valve plate also cooperates in directing pressure fluid to the inner ends of the vanes of the large pumping unit to maintain the outer ends of the vanes thereof in engagement with the inner contour of its cam ring.

It is also important to note that the separate rotors are maintained in fluid sealing engagement with the valve plate by pressure fluid means. In the case of the large pumping unit pressure fluid from the discharge side of the large pumping unit maintains the valve plate in fluid sealing engagement with the rotor of the large pumping unit. In the case of the smaller pumping unit pressure fluid from the discharge side of said unit maintains the cheek plate in fluid sealing engagement with the rotor and this in turn maintains the rotor in fluid sealing engagement with the valve plate. No mechanical adjustment, which in many cases results in pump failure because of excessive clamping pressure, is necessary for maintaining this fluid sealing engagement.

It should also be noted that several different combinations of sizes of the different pumping

units may be arranged. By mass production means, a variety of sizes of each section may be provided which may be combined to meet the demands of a variety of volumes and pressures of different circuits. In this manner, separate dual pumping units to meet each circuit requirement is obviated.

While the form of embodiment of the invention as herein disclosed constitutes a preferred form, it is to be understood that other forms might be adopted, all coming within the scope of the claims which follow.

What is claimed is as follows:

1. A dual vane pump comprising a casing having an inlet section and an outlet section between which is a first pumping unit, means forming a first pressure chamber in the outlet section having an outlet passage connected thereto, a first pressure responsive cheek plate in the first pressure chamber, one side of which is maintained in fluid sealing engagement against the first pumping unit, a second pumping unit on the opposite side of the first cheek plate, each pumping unit including means forming a pumping recess, a rotor in the recess, and a plurality of reciprocating vanes carried by the rotor, said vanes being held in bearing contact with the contour of the pumping recess to form suction and pressure working chambers, a common drive shaft for the rotors, a closure member mounted in the first pressure chamber and forming a second pressure chamber within the first pressure chamber, a second cheek plate in the second pressure chamber and pressure loaded against the second pumping unit, means forming an inlet supply flow path connected to the suction working chambers of both pumping units, means separately, respectively, connecting the pressure working chambers of the first and second pumping units to the first and second pressure chambers, a second outlet passage in the outlet section, and means hydraulically connecting the second pressure chamber to the second outlet passage.

2. A dual rotary pump comprising in combination a casing having two pumping units therein, each of which includes a stator and a rotor forming suction and pressure working chambers, a common drive shaft for driving the rotors, means forming an inlet supply path connected to the suction chambers respectively of both pumping units, means forming two pressure outlet chambers in the casing, one outlet chamber being inside the other outlet chamber, means separately, respectively, hydraulically connecting the pressure working chambers of the pumping units to the pressure outlet chambers, an outlet passage connected to the outer pressure outlet chamber, a second outlet passage for the inner pressure outlet chamber, and means hydraulically connecting the inner pressure outlet chamber to the second outlet passage.

3. A dual rotary pumping unit comprising in combination a casing having two pumping units therein, each of which includes a stator and a rotor forming suction and pressure working chambers, a common drive shaft for driving the rotors, means forming an inlet supply path connected to the suction chambers respectively of both pumping units, means forming two pressure outlet chambers in the casing, one outlet chamber being inside the other outlet chamber, means separately, respectively, hydraulically connecting the pressure working chambers of the pumping units to the pressure outlet chambers, an

outlet passage connected to the outer pressure outlet chamber, a second outlet passage for the inner pressure outlet chamber, and a telescoping fluid connection member hydraulically connecting the inner pressure outlet chamber to the second outlet passage.

4. A dual rotary pumping unit comprising in combination a casing having two pumping units therein, each of which includes a stator and a rotor forming suction and pressure working chambers, a common drive shaft for the rotors, means forming two pressure outlet chambers in the casing, one outlet chamber being inside the other outlet chamber, separate cheek plates for each pumping unit in each pressure outlet chamber and pressure loaded against their associated pumping units, means forming an inlet supply flow path to the suction working chambers of the pumping units, means separately, respectively, hydraulically connecting the pressure working chambers of the pumping units to the pressure outlet chambers, an outlet passage connected to the outer pressure outlet chamber, a second outlet passage for the inner pressure outlet chamber, and means hydraulically connecting the inner pressure outlet chamber to the second outlet passage.

5. A dual rotary pump comprising a first pumping unit and a second pumping unit, each pumping unit including a stator and a rotor forming suction and pressure working chambers, a common drive shaft for the rotors, a cheek plate between the pumping units in fluid sealing engagement therewith, means forming an inlet fluid supply flow path leading to the suction chamber of the first pumping unit and to the cheek plate, means forming two separate fluid delivery flow paths, one of which leads from the pressure chamber of the second pumping unit and the other of which leads from the cheek plate, and a fluid supply port and a fluid delivery port in the cheek plate respectively connecting the suction chamber of the second pumping unit to the inlet flow path and the pressure chamber of the first pumping unit to the other fluid delivery flow path.

6. A dual rotary pump comprising a first pumping unit and a second pumping unit, each pumping unit including a stator and a rotor forming suction and pressure working chambers, a common drive shaft for the rotors, a cheek plate floatably mounted between the pumping units, means forming an inlet fluid supply flow path leading to the suction chamber of the first pumping unit and to the cheek plate, means forming two separate fluid delivery flow paths, one of which leads from the pressure chamber of the second pumping unit and the other of which leads from the cheek plate, a fluid supply port and a fluid delivery port in the cheek plate respectively connecting the suction chamber of the second pumping unit to the inlet flow path and the pressure chamber of the first pumping unit to the other fluid delivery flow path, and pressure responsive means connected to the fluid delivery flow paths maintaining the cheek plate in fluid sealing engagement with both pumping units.

7. A dual rotary pump comprising a first pumping unit and a second pumping unit, each pumping unit including a stator and a rotor forming suction and pressure working chambers, a common drive shaft for the rotors, a cheek plate floatably mounted between the pumping units, means forming an inlet fluid supply flow

path leading to the suction chamber of the first pumping unit and to the cheek plate, means forming two separate fluid delivery flow paths, one of which leads from the pressure chamber of the second pumping unit and the other of which leads from the cheek plate, a fluid supply port and a fluid delivery port in the cheek plate respectively connecting the suction chamber of the second pumping unit to the inlet flow path and the pressure chamber of the first pumping unit to the other fluid delivery flow path, and separate pressure responsive means separately connected to the fluid delivery flow paths of the pumping units separately maintaining the rotors in fluid sealing engagement with the cheek plate.

8. A dual rotary pump comprising a first pumping unit and a second pumping unit, each pumping unit including a stator and a rotor forming suction and pressure working chambers, a common drive shaft for the rotors, a cheek plate floatably mounted between the pumping units, means forming an inlet fluid supply flow path leading to the suction chamber of the first pumping unit and to the cheek plate, means forming two separate fluid delivery flow paths, one of which leads from the pressure chamber of the second pumping unit and the other of which leads from the cheek plate, a fluid supply port and a fluid delivery port in the cheek plate respectively connecting the suction chamber of the second pumping unit to the inlet flow path and the pressure chamber of the first pumping unit to the other fluid delivery flow path, pressure responsive means including one side of the cheek plate in communication with one of the delivery flow paths for maintaining the cheek plate in fluid sealing engagement with one of the rotors, and a second pressure responsive cheek plate one side of which is in communication with the other delivery flow path for maintaining the other rotor in fluid sealing engagement with the first cheek plate.

9. A dual rotary vane pump comprising a casing provided with a pair of pumping recesses, a first pumping unit and a second pumping unit separately mounted in the recesses, each pumping unit including a rotor and a plurality of reciprocating vanes, said vanes being held in bearing contact with the contour of their respective pumping recesses to form suction and pressure working chambers, a common drive shaft for the rotors, a fluid distributing valve plate floatably mounted in the casing between the pumping units, means forming an inlet fluid supply flow path leading to the suction chamber of the first pumping unit and to the valve plate, means forming two separate fluid delivery flow paths, one of which leads from the pressure chamber of the second pumping unit and the other of which leads from the valve plate, a fluid supply port and a fluid delivery port in the valve plate respectively connecting the suction chamber of the second pumping unit to the inlet supply flow path and connecting the pressure chamber of the first pumping unit to the other fluid delivery flow path, pressure responsive means including one side of the valve plate in communication with one of the delivery flow paths for maintaining the valve plate in fluid sealing engagement with one of the rotors, and a pressure responsive cheek plate having one side thereof in communication with the other delivery flow path for maintaining the other rotor in fluid sealing engagement with the valve plate.

10. A dual rotary pump comprising a casing

having an inlet section and an outlet section between which is a first pumping unit, means forming a first pressure outlet chamber in the outlet section having an outlet passage connected thereto, a first pressure responsive cheek plate in the first pressure outlet chamber one side of which is maintained in fluid sealing engagement against the first pumping unit, a second pumping unit on the opposite side of the first cheek plate, each pumping unit including a stator and a rotor forming suction and pressure working chambers, a common drive shaft for the rotors, a closure member mounted in the first pressure outlet chamber and forming a second pressure outlet chamber within the first pressure outlet chamber, a second cheek plate in the second pressure outlet chamber and pressure loaded against the second pumping unit, means forming an inlet supply flow path leading from the inlet section to the suction working chambers of the pumping units, means forming two fluid delivery flow paths separately connecting the pressure working chambers of the first and second pumping units respectively to the first and second pressure outlet chambers, a second outlet passage in the outlet section, and means hydraulically connecting the second pressure outlet chamber to the second outlet passage.

11. A dual rotary pump comprising a casing having an inlet section and an outlet section between which is a first pumping unit, means forming a first pressure outlet chamber in the outlet section having an outlet passage connected thereto, a first pressure responsive cheek plate in the first pressure outlet chamber one side of which is

5 maintained in fluid sealing engagement against the first pumping unit, a second pumping unit on the opposite side of the first cheek plate, each pumping unit including a stator and a rotor forming suction and pressure working chambers, a common drive shaft for the rotors, a closure member mounted in the first pressure outlet chamber and forming a second pressure outlet chamber within the first pressure outlet chamber, a second cheek plate in the second pressure outlet chamber and pressure loaded against the second pumping unit, means forming an inlet supply flow path leading from the inlet section to the suction working chambers of the pumping units, means forming two fluid delivery flow paths separately connecting the pressure working chambers of the first and second pumping units respectively to the first and second pressure outlet chambers, a second outlet passage in the outlet section, and a telescopic connection from inside the second pressure outlet chamber to the second outlet passage.

25 DUNCAN B. GARDINER.
